UNITED STATES PATENT OFFICE

2,352,984

CIRCUIT BREAKER

Ludwig S. Walle, Lansdowne, Pa., assignor to General Electric Company, a corporation of New York

Application June 23, 1942, Serial No. 448,066

8 Claims. (Cl. 200—149)

My invention relates to circuit breakers, and particularly to gas-blast circuit breakers of the enclosed or compression chamber type.

Manually - operated current - responsive tripped circuit breakers are widely used for the connection and protection of branch circuits, particularly where large numbers of such circuit breakers must be grouped within a confined space. These breakers are depended upon to provide the short-circuit protection of a fuse as well as the advantages of a manually-operated switch. It has been found that the interruption of currents of short-circuit magnitude, for example, in excess of 10,000 amperes for a breaker having a normal rating of 225 amperes at 600 volts, may be very efficiently carried out in an enclosed or substantially enclosed chamber within which a gaseous dielectric at considerable pressure may be confined during the interruption.

While compression chamber interrupting units heretofore built have been quite successful in quenching arcs of short-circuit magnitude, they have been subject to certain drawbacks in operation and maintenance. For example, single break compression breakers must be very well sealed in order to build up sufficient pressure to insure positive interruption upon low currents. Such efficient sealing retains the high pressure generated by high currents for a relatively long time, thereby preventing prompt reclosing of the breaker. To make the chambers as gas-tight as possible, they have been assembled as unitary structures without means for access to the contacts. Such an arrangement contributes to the difficulty and expense of repair and replacement, since an inaccessible chamber must be removed and replaced as a unit, and the casing must be dismantled for repair. It is much more desirable from the viewpoint of manufacturing and maintenance facility to provide the chamber with a detachable cover or other such normally closed means for access to the contacts. From the operator's position a breaker with a substantial exhaust port for escape of gases will permit more immediate reclosure. In order to permit the use of a separable casing with an appreciable exhaust port, it is necessary to provide an interrupting unit which will function efficiently without the excessive gas pressures which have been used heretofore, and in which slight gas leakage from the casing during the interruption does not hamper the operation. I have found that in enclosed compression chamber interrupters, an electric arc may be interrupted even more efficiently at relatively low pressure than has heretofore

been effected at high pressure if means are provided for passing a blast of dielectric gas transversely of the arc, creating turbulence of the gas, and exhausting the gas through a constricted exhaust port at a point remote from the arc. The effect of the transverse gas blast and the turbulent flow is so enhanced by the presence of more than one break in a single chamber that a multi-break interrupter embodying my invention exhibits an interrupting capacity considerably larger than that ordinarily to be expected from the connection of an equal number of breaks in series circuit relation.

In order to assist in cooling the the arc, it is 15 desirable to generate the extinguishing gas within the compression chamber itself by permitting the arc to react upon gas emitting material. I have also found that in such enclosed breakers where the gas pressure is generated by the arc 20 itself, a greater efficiency may be attained if a gaseous dielectric under an initial pressure is present in the chamber prior to the drawing of the main arc. At the present time it appears that the presence of such an initial pressure enables the 25 arc to increase the gas pressure to interrupting value in a considerably shorter time and with considerably less maximum pressure.

Accordingly, it is one object of my invention to 30 provide a simple, reliable, and inexpensive circuit breaker of the compression chamber type.

It is another object of my invention to provide, in a circuit breaker of the above type, a compression chamber interrupting unit in which all parts are easily accessible for repair and replacement.

It is a further object of my invention to 35 provide a circuit breaker of the compression chamber type having means for establishing an arc-extinguishing gas blast transversely of the arc, creating turbulence in the gas flow, and cooling 40 and exhausting the gas from the chamber at a point remote from the arc.

It is a still further object of my invention to 45 provide a plural break compression chamber interrupter in which a dielectric gas under pressure is generated within the chamber by the action of the arc itself and automatically directed to have an optimum effect in extinguishing the generating arc.

It is a still further object of my invention to 50 provide gas-emitting means within a circuit interrupter of the compression chamber type arranged in intimate gas-generating relation with an electric arc to be interrupted and so constructed and arranged that gases emanating from 55 the gas-emitting means are forced to pass

through the arc in a direction substantially transverse thereto.

An even further object of my invention is to provide a circuit breaker of the compression chamber type with means for establishing an initial pressure within the chamber prior to the drawing of the main arc.

In carrying out my invention in one form, I provide a metallic pressure-confining casing comprising a base and a detachable cover and provided with a liner or gasket of suitable arc-resisting compound. Within the casing I arrange a pair of stationary contacts and a pivotally mounted E-shaped bridging contact arranged to form an electrical connection between the stationary contacts. The E-shaped bridging contact is loosely connected, preferably pivotally and below its center of gravity, to a movable actuating arm and is provided at the extremities of its outer arms with suitable contact elements. The stationary contacts are partially enclosed within insulator means of gas-emitting material, the stationary contacts being positioned well within and closely adjacent the insulator. Preferably each stationary contact is located within a separate generally cup-shaped insulator. Where separate insulators are used each insulator may be apertured at one side to permit exhaust of the gases generated therein transversely across the generating arc. Preferably also such aperture of each separate cup-shaped insulator is disposed on the side adjacent the other insulator, so that the streams of gas exhausted from the cups will be directed oppositely and in encountering each other will create within the interrupting chamber a great turbulence of gas flow which further enhances the interrupting capacity of the breaker. With such an arrangement it is also believed that, due to the fact that the E-shaped bridging contact is mounted in a position of unstable equilibrium, the stationary contacts are rarely disengaged simultaneously, so that one arc is always formed before the other. In this way the first arc formed acts as a pressure-generating arc which establishes an initial gas pressure in the casing prior to the drawing of a main arc of the contact last to open. The metallic casing is apertured to provide a constricted exhaust port which is connected with the interior of the casing through the tortuous passageways of a gas-cooling device.

My invention itself will be better understood and its objects and advantages further appreciated by referring now to the following detailed specification taken in conjunction with the accompanying drawing in which Fig. 1 is a plan view of a circuit breaker embodying my invention, the outside casing being partially broken away and the cover of one of the interrupting units being removed in order more clearly to illustrate the details of construction; Fig. 2 is a side view of the circuit breaker, one of the interrupting units being shown in section; and Fig. 3 is an exploded perspective view of the gas-cooling chamber shown at Fig. 2, certain parts being broken away in order more clearly to illustrate the parts below.

Referring now to the drawing, and particularly to Figs. 1 and 2, I have shown a circuit-breaker mounted upon an insulating base 10 and provided with an insulating cover 11. Preferably the base 10 and cover 11 are formed of a molded insulating compound of which many types are well known to those skilled in the art. Mounted upon the base 10 at one end is a suitable snap-

acting operating mechanism (not shown). Such a mechanism may be of the type described and claimed in Patent 2,169,085, issued to W. A. Atwood on August 8, 1939. As shown in the patent referred to, the mechanism is preferably of the manually-operated current-responsively tripped type and is connected to operate a crank arm 12 which is rigidly connected to an operating shaft 13. An operating handle 14 projects through the cover 11 for convenient control of the mechanism. Mounted upon the opposite end of the base 10 and within the cover 11, I provide a plurality of enclosed compression chambers, each comprising a steel base 15 and a steel cover 16. While I have shown for purposes of illustration a three-phase breaker having a separate compression chamber for each phase of the circuit and a single interrupting device within each chamber, I wish to have it understood that any desired number of such individual enclosed interrupting units may be connected to a single operating mechanism or that, if desired, a plurality of interrupting devices may be arranged within a single compression chamber. In the breaker shown, all the chambers are of similar construction and, therefore, only one chamber will be described in detail.

The base of each chamber is lined at the bottom and sides with a liner 17, the side walls of which extend upwardly to provide a liner for a portion of the cover 16. The liner 17 is provided with a peripheral flange 18, arranged as a gasket between the abutting edges of the base 15 and cover 16, thereby to form a gas-tight seal between the parts of the steel chamber. The liner is made of arc-resisting insulating material, and preferably consists of a molded, synthetic, rubber-like, arc-resisting compound, such as a plasticized polyvinyl chloride. Small strips 19 of the same material are provided in the upper part of the steel cover 16 to insulate the current-carrying movable contact from the casing. In order that the steel cover 16 be readily detachable, a pair of bearings 20 for the operating shaft 13 are molded as integral parts of the liner 17 at opposite sides of one end thereof. While I prefer to mold the shaft bearings 20 in the liner 17 for simplicity of manufacture and assembly, I wish to have it understood that I do not desire to be limited to such an arrangement, but that the bearings may be provided in connection with other portions of the contact chamber. To facilitate easy removal of the compression chamber cover 16, the cover and base are held together by a single centrally-located bolt 24 and a nut 25. The nut 25 is permanently fixed in place upon the steel base 15 so that removal and replacement of the cover may be effected simply by removal and replacement of the bolt 24. The bolt 24 is also internally threaded at its end for cooperation with a fixed stud 26 thereby to connect the compression chamber as a unit to the base 10.

The stationary contact structure comprises a pair of fixed contacts 27 and 28 having V-shaped tip portions 29 and 30, respectively. While the body of the contacts 27 and 28 may be of copper or other material having a relatively high conductivity, the V-shaped tips 29 are preferably formed of a material which, while a good electrical conductor, also possesses a high degree of arc-resistivity. For example, one material which may be used for the contact tips 29 and 30 to obtain long life and minimum burning comprises an alloy of sintered tungsten impregnated with copper, silver or the like material. Such an alloy

is described and claimed in Patent 1,552,184, issued to Nathan H. Adams on September 1, 1925.

Each stationary contact 27, 28 is mounted in the base of a substantially cylindrical insulator cup 31 in such manner that the contact tips 29 and 30 lie within the base of the cup, and the shank portion of the contact extends through the base of the cup where it terminates in a threaded portion 32, arranged for connection with a suitable electrical conductor. A rubber washer 32a is positioned between each contact tip and the base of the associated insulator cup 31. As will be observed from Fig. 2, the upwardly-extending cylindrical portions of the insulator cups 31 define restricted spaces in which electric arcs between the stationary contacts and the bridging contact must be drawn and are positioned in close proximity to the arc paths. The cups 31 are also apertured at their adjacent sides, as at 32b, to accommodate the downwardly-extending outer legs of an E-shaped bridging contact 33. The stationary contacts may be located as closely together as mechanical and electrical limitations permit.

As is well known to those skilled in the art, gas under substantial pressure is possessed of considerable dielectric strength and facilitates the rapid quenching of an electric arc. Furthermore, a blast of gas through an arc, and especially substantially transversely therethrough, aids in cooling and quickly deionizing the arc thereby rapidly to extinguish it. With a view to combining these effects, I form the insulating cup 31 of a molded gas-emitting material in order to supply a gas under pressure from a source within the compression chamber and specifically from a source within the restricted space defined by the insulator cup. I also shape the cups in the manner described above for the purpose of directing the exhausted gases generated within the cups in opposing directions and substantially transverse of the generating arcs. Many suitable gas-emitting materials are well known to those skilled in the art. For example, one such material which I consider to be particularly suitable for this purpose comprises polymerized methyl methacrylate, a filler of quartz, magnesia, alumina, flint, wood flour, china clay, asbestos, spun glass in woven form, mica, or the like, in combination with a gas-emitting material, such as urea, urea-formaldehyde resins, urea phosphates, or other compounds of urea, ammonium carbonate or ammonium bicarbonate or other organic or inorganic substances which in the circuit-interrupting process emit gases (nitrogen, carbon dioxide, water vapor, etc.) having arc-extinguishing properties.

It will be understood that the gas-emitting insulators 31 are positioned closely adjacent each of the contacts so that arcs formed at the contacts will be brought into intimate gas-generating relation with the insulators. The more completely the insulators enclose the contacts the greater will be the insulating effect because of the increased length of the creepage path between the contacts. On the other hand, the apertures 32b at the sides of the insulators serve to provide an exhaust passage for gases formed within the cups so located that in exhausting from the cups the gas streams must pass substantially transversely across the generating arcs. This effect is enhanced by the fact that the moving contacts themselves substantially close the upper ends of the insulating cups. It is well known that a gas blast transverse to an electric arc is more effec-

tive in quenching the arc than a gas blast directed longitudinally of the arc. Furthermore, by aperturing my cup-shaped gas-emitting insulators on the sides adjacent each other, I not only force the gases produced within each cup to cross the generating arc in a substantially transverse direction but also to emerge from the cup in a direction opposed to the blast from the other cup. In this manner the gas blasts encounter each other immediately after they emerge from the cups thereby to create a great turbulence of gas flow and to force both blasts upwardly into cooler air, and ultimately outside of the compression chamber through an exhaust port remotely located with respect to the arcs. The exhaust port will be more fully described hereinafter.

To complete the stationary contact structure, the lower end or shank portion of each contact 27, 28 is enclosed within a second cup-shaped insulator 34 apertured at its base to receive a clamping nut 35 for threadingly engaging a portion 32 of each contact. The insulators 34 are located outside the pressure-confining chamber and, since they are not acted upon by the arc, need have no gas-emitting properties. Thus each stationary contact 27, 28 acts as a bolt which in cooperation with the nut 35 clamps the cup-shaped insulators 31 and 34 to opposite sides of the steel base 15 and serves electrically to connect the contact tips 29 and 30 to suitably apertured lead-in conductors 40 and 41, which are held in clamped engagement between the insulators 34 and the heads of the nuts 35. The compression chamber itself is attached to the base 10 by the stud 26 which threadingly engages the inner surface of the bolt 24.

Electrical connection between the stationary contacts 29 and 30 is formed by the E-shaped bridging contact 33. The bridging contact comprises a pair of conducting plates 42 and 43 fixed in parallel spaced relation by a pair of transverse pins 44 and 45 and carrying upon their downwardly extending outer arm suitable diverging and laterally resilient contact tips for engagement with the V-shaped stationary contact tips 29 and 30. The central portions of the E-shaped plates 42 and 43 are laterally offset as may be observed at Fig. 1 in order to widen the space therebetween for accommodation of the bolt 24.

The E-shaped bridging contact 33 is pivotally supported, preferably at a point directly below its center of gravity, upon a pair of L-shaped actuating arms 47. Each actuating arm 47 has one long and one short leg and is nonrotatably attached at the end of the long leg to the operating shaft 13 thereby rotatably to mount the bridging contact 33 upon the shaft 13. The short leg of each actuating arm 47 lies alongside the center arm of one of the E-shaped contact plates 42, 43 in substantially parallel spaced relation therewith and is pivotally attached thereto at its outer end by means of a pivot pin 48. The actuating arms 47 are laterally resilient and are each biased inwardly to hold the E-shaped plates of the bridging contact 33 together and to provide an initial contact pressure. Thus the E-shaped bridging contact 33 is mounted at a point lying substantially directly below its center of gravity and on a straight line between the contact tips 46. In order to limit relative rotation of the bridging contact 33 with respect to the actuating arms 47, pin and slot connections 49,

58 are provided between these members at points spaced from the pins 48.

As may best be observed at Fig. 2, the slots 58 are of such length that in the circuit-opening position of the interrupting unit the bridging contact 33 may be flat against the top of the pressure-confining chamber 15, 16 in substantially parallel spaced relation thereto, so that the ultimate break distance of each pair of co-operating fixed and movable contacts is substantially the same. It will be understood, of course, that when the interrupter is in its circuit-closing position, the bridging contact 33 is in its lowermost position and also lies with its back in substantially parallel spaced relation to the top surface of the pressure-confining chamber. The slots 58 must be of only sufficient length to permit the bridging contact 33 to assume these two limiting positions with respect to the actuating arms 47. It will be observed that in any position intermediate its uppermost and lowermost positions the bridging contact 33 will be supported upon the pin 48 in a position of unstable equilibrium if its back lies in parallel spaced relation with the upper surface of the casing 16.

Harmless escape of hot gases is provided through a pair of centrally bored screws 55 in the top of each steel chamber cover 16 at a point remote from the contact tip. The central bore of the screws 55 provides constricted exhaust ports, while the screws themselves serve to attach to the inside of each cover 16 a gas-cooling baffle and muffling chamber 56 shown in detail at Fig. 3. It will be understood that the exhaust ports are constricted in the sense that they are sufficiently small to permit build-up of appreciable gas pressure during the interrupting period, but they are also sufficiently large to limit the pressure and to permit rapid exhaust after interruption. Each gas cooler 56 comprises a box-like metallic container 57 having a turned-over flange 58 apertured at 59 to form gas entrance ports. The container 57 is divided into two connected compartments by a baffle plate 60, the length of which is somewhat less than the length of the container 57. Within the upper compartment are arranged a pair of permanently attached or integrally formed nuts 65 for threadingly engaging the hollow screws 55, while the lower compartment contains a heat-absorbing and muffling means such as, for example, a tumbled heat 66 of short lengths of copper tubing. The structure of the gas cooler is completed by a box-like cover 67 which slips over the container 57 and is provided with entrance ports 68 registering with the entrance ports 59 and bolt holes 69 registering with bolt holes 70 in the container 57. It will now be observed that the exhaust gases entering the gas cooler at the ports 59 and 68 must first pass along the full length of the lower compartment in contact with the heat-absorbing mass 66 and then along substantially the full length of the upper compartment before reaching the exhaust port of the hollow screws 55.

Since the exhaust port has no critical effect upon the arc interruption, such as by direction of a gas blast across or along an arc, it may be located anywhere within the casing which is relatively remote from the arcs themselves. Similarly, slight leakage of gas through imperfect joints in the pressure-confining chamber, as through the joints between the casing space 15 and casing cover 16, will have no appreciable effect upon the arc-interrupting capacity of the

breaker. It will therefore be understood that by the term "constricted exhaust port," when used in the claims, I mean any exhaust opening, whether specifically provided or constituted of accidentally or intentionally loose joints or fittings, which is sufficiently small to permit a temporary build-up of pressure within the casing while arc gas is being generated and which is sufficiently large to effect a reduction of the pressure and exhaust of the gases from the casing within a reasonable time after the arc interruption.

In operation, when the crank arm 12 is rotated by the operating mechanism in a clockwise direction as viewed in Fig. 2, the contact-carrying end of the actuating arms 47 is raised to move the bridging contact 33 from its circuit-closing position to its circuit-opening position. During this movement, and before the movable contact tips 46 are withdrawn from the upper ends of the cup-shaped gas-emitting insulators 31, an electric arc is drawn between each pair of fixed and movable contacts and within each cup-shaped insulator. Due to the fact that the bridging contact is formed in the shape of an E with its contact tips positioned at the depending ends of its outer arms, the two arcs will be positioned in parallel spaced relation with the arc current flowing in opposite directions. This results in a concentration of magnetic lines of force between the gas-emitting insulator cup 31 thereby forcing the arcs to bow outwardly in a manner well known to those skilled in the art. Thus by magnetic repulsion each arc is forced against the outer side of its associated insulator cup and into intimate gas-emitting contact with the cup, thereby facilitating generation of gas within the pressure-confining chamber. Because of the fact that the arc interruption takes place over a very short time interval and also because of the fact that the exhaust ports 75 are quite constricted and positioned at a remote point with respect to the point of generation of the gas, a considerable pressure is quickly built up within the chamber 15, 16. Furthermore, since the gas is generated within each of the insulating cups 31, the greatest pressure exists within the restricted space inside the cups in the immediate region of the arc, and there is therefore a definite tendency to force the gas out of the cups and into the interior of the compression chamber 15, 16. Since this action takes place largely before the movable contact tips 46 emerge from the upper ends of the cups 31, the path of least resistance for the exhaust of gases from the cups is through the apertures 32b on the inner sides of the cups. As each gas stream passes outwardly through the aperture 32b into the space between the insulator cups 31, it is forced substantially transversely across the path of the generating arc. This transverse gas-blast effect arises largely from the fact that the major portion of the gas is generated at the outer side of each insulator cup due to the magnetic bowing effect, while the lateral exhaust apertures in the cups are located on the inner or adjacent sides of the cups.

As explained in the preceding paragraph, the stream of dielectric gas emanating from each cup 31 is directed inwardly toward the central bolt 24 so that these gas streams emerge from the cups in opposing directions and encounter each other with some degree of violence. The violent impact of the gas streams creates an appreciable turbulent flow of gas in the central and upper portion of the chamber 15, 16, and the turbulence

thus created appears to have a beneficial effect in interrupting the arcs. This effect may be due to the fact that each particle of gas, due to the turbulent flow, encounters the arc a number of times.

It has been previously noted that while in its circuit-closing position the bridging contact 33 is retained with its back in substantially parallel spaced relation with the upper surface of the cover 16 because of its engagement with the stationary contacts 29 and 30, and while in its circuit-opening position it is retained in a similar position by engagement with the top of the casing cover 16, this parallel position of the bridging contact 33 is one of unstable equilibrium at any intermediate position of the actuating arms 47. Thus as soon as the circuit-opening movement of the actuating arm 47 begins, the bridging contact 33 is placed in a position of unstable equilibrium, due to the fact that it is loosely mounted at a point directly below its center of gravity. It will therefore be evident that it is extremely unlikely that breaks will be made exactly simultaneously between each pair of fixed and movable contacts, especially since there almost certainly will exist a slight difference in the amount of friction between each pair of contacts. Accordingly, the two series breaks will be formed sequentially rather than simultaneously, so that the first arc to be drawn may be regarded as a pressure-generating arc. It is unlikely that this pressure-generating arc attains any substantial length before an arc is drawn at the other pair of contacts, but apparently it is sufficient to build up within the chamber 15, 16 a considerable initial pressure prior to the drawing of the second or main arc between the other pair of contact tips. The existence of such a gaseous dielectric under an initial pressure prior to the drawing of the second arc facilitates a more rapid quenching of both arcs and permits the interruption of a current of any predetermined short-circuit magnitude within a much more confined space than has heretofore been considered possible.

While I have described but one embodiment of my invention by way of illustration, many modifications will occur to those skilled in the art and I therefore wish to have it understood that I intend by the appended claims to cover all such modifications as fall within the true spirit and scope of my invention.

What I claim as new and desire to secure by Letters Patent of the United States is:

1. A circuit breaker adapted to interrupt currents of short-circuit magnitude comprising a pressure-confining chamber provided with a constricted exhaust port, a plurality of pairs of separable switch contacts mounted within said casing remote from said exhaust port, said pairs of contacts being connected in series circuit relation, movable means for separating said pairs of contacts to establish electric arcs therebetween, means within said casing for partially enclosing each of said pairs of separable switch contacts thereby to define within said casing a restricted space for the separation of each of said pairs of contacts, means within each of said enclosing means operable in conjunction with the electric arc established between the associated pair of separable contacts for generating within said enclosing means a dielectric gas at substantial pressure, and means for exhausting said gaseous dielectric from each of said enclosing means into the interior of said casing in opposing directions, the stream of gas from each of said enclosing

means passing substantially transversely across the generating arc and encountering the opposing stream of gas to create within said casing a turbulent flow of gas between said contacts and said exhaust port and said casing confining said gas to create within said casing a pressure sufficient to prevent short-circuiting of said pairs of contacts by said opposing gas streams.

2. A circuit breaker adapted to interrupt currents of short-circuit magnitude comprising a pressure-confining casing provided with a constricted exhaust port, a plurality of pairs of fixed and movable circuit-interrupting contacts mounted within said casing, said pairs of contacts being connected in series circuit relation, a generally cup-shaped insulator of gas-emitting material partially surrounding each of said fixed contacts, said insulators being apertured at adjacent sides thereof to permit the escape of dielectric gases generated therein, operating means common to said movable contacts for actuating said contacts from a circuit-closing to a circuit-opening position thereby to establish an electric arc between each of said pairs of contacts and at least partially within the enclosing gas-emitting insulator, and means for causing said arcs to impinge upon said insulators opposite said apertures so that dielectric gases generated thereby must pass toward said apertures in streams substantially transverse to the generating arcs, said gas streams encountering each other upon emergence from said insulators thereby to create within said pressure-confining casing a turbulent flow of gas under a pressure sufficient to prevent short-circuiting of said pairs of contacts by said encountering gas streams.

3. An air circuit breaker adapted to interrupt currents of short-circuit magnitude comprising a pressure-confining casing provided with a constricted exhaust port, a pair of stationary contacts mounted in side-by-side relation within said casing, a generally cup-shaped insulator of gas-emitting material partially enclosing each of said fixed contacts, each of said insulators being apertured on the side adjacent the other of said insulators thereby to permit the escape of hot gases in opposing and encountering streams passing transversely with respect to generating electric arcs formed within said insulators, a movably mounted bridging contact within said casing having its ends arranged to project within said insulators thereby to engage said fixed contacts and to connect said contacts together in series circuit relation, and actuating means for moving said bridging contact from a circuit-closing to a circuit-opening position to establish an electric arc within each of said insulators, whereby the transverse gas-blast effect of each escaping stream of gas and the turbulent flow resulting from their interaction upon each other combine to assist in the quenching of said arcs while the pressure of said gas within said casing is sufficient to prevent short-circuiting of said stationary contacts by said encountering gas streams.

4. An air circuit breaker adapted to interrupt currents of short-circuit magnitude comprising a pressure-confining casing provided with a constricted exhaust port, a pair of stationary contacts mounted within said casing, a bridging contact movably mounted within said casing for actuation between circuit-closing and circuit-opening positions, said bridging contact when moved from said circuit-closing position establishing with said stationary contacts a pair of electric arcs in parallel spaced relation, and gas-emitting means

partially enclosing each of said stationary contacts in intimate gas-generating relation with said arcs, said gas-emitting means being so disposed that the mutual magnetic blowout effect of said arcs induces said arcs to impinge upon said gas-emitting means thereby to establish within said casing a gaseous dielectric under pressure and being apertured on adjacent sides to direct exhaust gases from said gas-emitting means in opposing and encountering streams passing transversely of the generating arc, the pressure of said dielectric within said casing being sufficient to prevent short-circuiting of said stationary contacts by said encountering gas streams.

5. An air circuit breaker adapted to interrupt currents of short-circuit magnitude comprising a pressure-confining casing provided with a constricted exhaust port, a pair of stationary contacts mounted within said casing, a bridging contact loosely mounted within said casing for movement between circuit-closing and circuit-opening positions, said bridging contact when moved from said circuit-closing position establishing a pair of electric arcs in substantially parallel spaced relation, and gas-emitting insulator means partially enclosing each of said stationary contacts to present gas-emitting surfaces in intimate gas-generating relation with respect to said arcs, said insulator means being formed to provide exhaust passages for the gases generated therein from said insulator means to the interior of said casing, said exhaust passages directing said gases in separate streams transversely across the generating arcs and into engagement with each other to create within said casing a turbulent flow of gas under pressure, said pressure resulting from the constriction of said exhaust port and being sufficient to prevent short-circuiting of said stationary contacts by said encountering gas streams.

6. An air circuit breaker adapted to interrupt currents of short-circuit magnitude comprising a pressure-confining casing provided with a constricted exhaust port, a pair of stationary contacts mounted within said casing in side-by-side relation and remote from said exhaust port, a bridging contact loosely mounted within said casing for movement between circuit-closing and circuit-opening positions, said bridging contact when moved from said circuit-closing position establishing a pair of electric arcs positioned substantially in parallel spaced relation and electrically connected in series circuit relation, and gas-emitting insulator means positioned closely adjacent said stationary contacts and arranged partially to enclose said electric arcs, the mutual magnetic blowout effect of said electric arcs causing said arcs to impinge upon said insulator means thereby to generate in the region of said arcs a volume of dielectric gas under pressure, said insulator means being formed to provide exhaust passages from the interior thereof to the interior of said casing, said exhaust passages being positioned to direct said gas into said casing in opposing and encountering streams each pass-

ing substantially transversely across the generating arc, whereby said opposing streams create within said casing a turbulent flow of gas to assist in the quenching of said arcs and under a pressure sufficient to prevent short-circuiting of said stationary contacts by said encountering gas streams.

7. An air circuit breaker adapted to interrupt currents of short-circuit magnitude comprising a pressure-confining casing provided with a constricted exhaust port, a plurality of pairs of separable switch contacts within said casing, said pairs of contacts being connected in series circuit relation and arranged when separated to establish a pair of electric arcs positioned in substantially parallel spaced relation, gas-emitting insulator means positioned closely adjacent each of said pairs of contacts and arranged partially to enclose said electric arcs, the mutual magnetic blowout effect of said electric arcs causing said arcs to impinge upon said insulator means thereby to generate in the region of said arcs a quantity of dielectric gas under pressure, said insulator means being formed to provide exhaust passages from the space enclosed thereby to the interior of said casing, said exhaust passages being positioned to direct said gas into said casing in opposing and encountering streams each passing substantially transversely across the generating arc, and common actuating means for separating both said pairs of contacts, whereby said opposing streams of gas create a transverse gas-blast effect upon each of said arcs and interact to create within said casing a turbulent flow of gas between said contacts and said exhaust port thereby to assist in the quenching of said arcs, the pressure of said gas within said casing being sufficient to prevent short-circuiting of said pairs of contacts by said encountering gas streams.

8. An arc extinguishing circuit interrupter of the air break type comprising a pressure-confining casing, a plurality of pairs of separable switch contacts, a substantially cylindrical cup-like insulator of gas-evolving material at least partially enclosing each of said pairs of contacts, said insulators being disposed in substantially parallel spaced relation and being apertured on adjacent sides to provide gas exhaust passages in opposing relation, operating means for separating said pairs of contacts substantially simultaneously to establish electric arcs within said insulators and in intimate gas-generating relation with the sides of said insulators opposite said apertures, whereby the dielectric gases evolved within said insulators pass substantially transversely of the generating arcs and through said apertures in opposing and encountering streams to create between said insulators a turbulent flow of gas to aid the quenching of said arc, said gases creating within said casing a pressure sufficient to prevent short-circuiting of said pairs of contacts by said encountering gas streams.

LUDWIG S. WALLE.
